UNITED STATES PATENT OFFICE

JOSEPH J. RATHGEB, JR., OF NEW YORK, N. Y.

AUTOMATIC FEEDING DEVICE FOR GRATES

Application filed October 26, 1926. Serial No. 144,241.

The present invention relates to boilers and furnaces and has for its principal object the production of an automatic stoker of simplicity of construction and of ease of assembly which shall preferably be of the "over-head" type and which shall be adapted to uniformly and evenly distribute fresh fuel to the fire bed to thereby materially reduce the cost of operation of stoking.

10 Other and further objects and advantages of the invention will appear from the accompanying description, the invention consisting in the novel automatic stoker and parts thereof hereinafter more particularly described and then specified in the claims.

In the accompanying drawings I have illustrated a practical embodiment of the invention in which:

Fig. 1 is a side elevation of the stoker positioned in operative relation to a boiler.

Fig. 2 is an enlarged vertical sectional view on the line 2—2 of Fig. 1.

Fig. 3 is an enlarged vertical cross-section on the line 3—3 of Fig. 2.

Fig. 4 is a vertical cross-section on the line 4—4 of Fig. 2.

Fig. 5 is a cross-section on the line 5—5 of Fig. 1.

Referring in detail to the several figures of the drawings:

The furnace may be of any conventional type and as shown includes the front and rear walls 1 and 2 joined together by the top wall 3, the grate being indicated diagrammatically at 4. The furnace is provided with the usual feed door 5 leading into the fire box and immediately above this door the front wall 1 is provided with an elongated feed opening 6 the upper and lower walls of which are preferably curved as illustrated in Fig. 4, the general direction of said opening being inclined to the vertical as shown.

The stoker includes front and rear side members 7 and 8 which are joined together by cross struts 9 and an upper member 10. Said

upper member supports an elongated fuel hopper 11, which may be secured thereto in any desirable manner, the frame itself being placed immediately in front of the furnace adjacent the feed door 5 and feed opening 6. The lower portion of the body of said fuel hopper adjacent its outlet has rounded walls 12 forming a space through which a shaft 13 extends which shaft is journalled in suitable bearings 14. Said shaft has rigidly mounted thereon a series of star-shaped elements 15, the pointed portions of each element being located in staggered relation to the pointed portion on the adjacent element. When in assembled position on said shaft 13 said elements constitute a distributing device adapted to distribute the fuel in the hopper evenly through its outlet opening.

Fuel is conveyed from the hopper 11 to the furnace through a suitable conduit shown as comprising an outlet section 16 attached to or integral with the hopper, conduit sections 17 and 18 pivotally connected to one another and to the hopper outlet 16 and a delivery conduit 19, pivotally connected to the section 18. The members 16, 17, 18 and 19 are of general rectangular shape in cross-section, each of the sections discharging into the next lower section by gravity.

The delivery conduit 19 is formed with curved walls 35 extending transversely across the same for receiving a wheel 36. The wheel 36 is supported upon a supporting shaft 34 and is formed with a series of radial vanes or blades 37 formed of a radial length such that they substantially engage the inner surface of the curved walls 35. The blades 37 are so spaced circumferentially about the axis of rotation thereof that one or more of the blades 37 engage each of the curved walls 35 at all times. The wheel thus closes communication between the inlet end of the delivery conduit and the discharge outlet 38 leading therefrom except when the wheel 36 is in operation. The delivery conduit 19

is movably supported by means of transversely arranged lugs 40 formed on the conduit and provided with outer curved surfaces 39 corresponding to the surfaces 6 in the furnace wall and engaged therewith. The delivery conduit 19 is thereby supported for rocking movement about the axis of curvature of the surfaces 39 and 6.

The delivery conduit 19 is rocked and the connecting conduit 18 is simultaneously moved by means of a pitman 23 pivotally connected with the conduit section 18 and with a crank 22 formed on an intermediate drive shaft 20 rotatably supported as by means of bearings 21. Rotation of the shaft 20 oscillates the conduit section 18 so as to prevent fuel from clogging in the conduit, the movement of the delivery conduit 19 varying the angle of inclination thereof to distribute the fuel more uniformly in the furnace.

The apparatus is operated by means of an electric motor 30 supplied with current from an outside source. The drive pulley 29 of the motor is connected by a belt 28 to the driving pulley 27 secured on the intermediate shaft 22. The shaft 22 is operatively connected with the shaft 13 by means of the belt 26 and the supporting pulleys 24 and 25 and to the shaft 34 by means of the belt 32 and pulleys 31 and 33. In order to rotate the shaft 34 and wheel 36 at a higher rate of speed than the feeding shaft 13, the pulley 31 is substantially larger than the driven pulley wheel 33 whereas the drive pulley 25 has the same or a smaller diameter than the pulley 24. This arrangement assures a faster rotation of the wheel 36 than the wheel 15 so that the former will at no time clog up or obstruct the outward passage of fuel through the section 19 while the two shafts 13 and 34 are being rotated the speed of rotation of the wheel 36 forcing the fuel into the furnace at a relatively high velocity, thus further assisting in the even distribution of the fuel in the fire box. To maintain an operating tension on the belt 32 while conduit 19 oscillates about its axis within the furnace wall I provide a pivoted bar 41 carrying a pulley 42 which is held in engagement with said belt 32 by the action of a spring 43.

In the operation of the apparatus current is supplied to the motor 30 either automatically or manually, causing the shafts 13, 20, and 34 to rotate. Rotation of the shaft 13 produces a uniform discharge of fuel from the hopper into the conduit leading to the discharge outlet 38. Rotation of the shaft 34 causes the fuel to be discharged forcibly from the outlet opening 38 of the conduit. The oscillation of the sections 17, 18, 19 prevents any accumulation or packing of fuel in the conduit and also varies the angle of inclination of the section 19 of the conduit and distributes the fuel evenly in the furnace.

When the feeding devices are not in operation the wheel 36 operates as a closure to prevent the passage of air into the furnace on the upper surface of the coal-bed and also prevents the passage of flames from the furnace into the fuel conduit leading to the hopper. 70

What I claim as my invention is:

1. In an automatic stoker for furnaces, a fuel hopper, a fuel feeding device associated therewith for evenly and continuously feeding a limited quantity of fuel therefrom, a pivotally supported delivery conduit, means for positively forcing the fuel from said delivery conduit, the capacity of said means being greater than the capacity of said fuel feeding device, a connecting conduit pivotally connected to said delivery conduit and constructed for conducting fuel from said hopper to said delivery conduit, means for oscillating said delivery conduit and connecting conduit and means for actuating said fuel feeding device and said first named means. 75

2. In combination with a furnace having an opening in a wall thereof provided with curved walls, a fuel hopper, an oscillating delivery conduit extending through said opening and into said furnace from a point without the same, a connecting conduit extending from said hopper to said delivery conduit for conducting fuel from said hopper to said conduit, lug members on said delivery conduit formed with curved engagement surfaces engaging said curved walls of said opening to permit rocking movement of said delivery conduit about a horizontal axis and means for oscillating said delivery conduit. 80

3. In combination with a furnace having an opening in a wall thereof provided with curved walls, a fuel hopper, an oscillating delivery conduit extending through said opening and into said furnace and having a portion positioned without the furnace, 85 said delivery conduit being supported within said opening by means permitting rocking movement of said delivery conduit about a horizontal axis, a conducting conduit extending from said fuel hopper to said delivery conduit for conducting fuel from said hopper to said conduit, means for rocking said delivery conduit and operative means in the portion of said delivery conduit without said furnace for advancing fuel through 90 the same when operated and for closing the passage therethrough when not in operation. 105

4. In combination with a furnace having an inclined transversely extending opening in a wall thereof, said opening being provided with transversely curved upper and lower walls, a fuel hopper formed with a transverse elongated opening, a transversely elongated delivery conduit engaging and interfitting with said curved walls to form a piv- 110 120 125 130

oted support for said delivery conduit, a transversely elongated conduit formed of sections pivotally connected together and to said delivery conduit for conducting fuel from said hopper to said delivery conduit, means for feeding fuel from said hopper into said conduit, and means for oscillating a section of said conduit and simultaneously rocking said delivery conduit on its pivot whereby the delivery end thereof will oscillate about a horizontal axis.

Signed at New York, in the county of New York and State of New York this 25th day of October A. D. 1926.
